FOUNTAIN PEN

Rose R. Eratico, Long Island City, N. Y.

Application June 19, 1948, Serial No. 34,050

3 Claims. (Cl. 120—46)

1

The present invention relates to writing implements, and more particularly to fountain pens.

The object of the present invention is to provide a fountain pen equipped with a simple device for filling same.

A further object of the present invention is to provide a fountain pen which may be readily filled in an efficient manner.

Another object of the present invention is to provide a fountain pen which can be manufactured at low costs.

With the above and other objects of the invention in view, the invention consists in the novel construction, arrangement and combination of various devices, elements and parts as set forth in the claims hereof, certain embodiments of the same being described in the specification and being illustrated in the accompanying drawings forming part of this specification, wherein:

Fig. 1 is a longitudinal sectional view of a fountain pen according to the invention.

Fig. 2 is a longitudinal sectional view of the fountain pen similar to that shown in Fig. 1, wherein, however, the covering shell and the cap are omitted, and wherein elements of the filling device are in a different position.

Fig. 3 is a sectional view taken on line 3—3 of Fig. 1.

Fig. 4 is a sectional view taken on line 4—4 of Fig. 1.

Fig. 5 is a sectional view taken on line 5—5 of Fig. 2.

Fig. 6 is a longitudinal sectional view of another embodiment of a fountain pen according to the invention, the covering shell and the cap being omitted.

Fig. 7 is a longitudinal sectional view of the fountain pen shown in Fig. 6, wherein however the elements of the filling device are in different positions.

Fig. 8 is a sectional view taken on line 8—8 of Fig. 6.

Fig. 9 is a sectional view taken on line 9—9 of Fig. 7, and

Fig. 10 is a fragmentary longitudinal sectional view of the fountain pen shown in Figs. 6 and 7 illustrating the connection of an ink supply sack with a nib holder.

Referring now to Figs. 1—5, 20 indicates a barrel of tubular shape. Said barrel 20 is open at both ends.

A nib holder generally indicated by 22 is inserted into the right-hand-end of the barrel 20 as viewed in Figs. 1 and 2. Said nib holder 22 has

a cylindrical portion 24 tightly fitting into the bore of the barrel 20. A shoulder formed between said cylindrical portion 24 and the projecting portion 26 of the nib holder 22 acts as an abutment cooperating with the right-hand-end surface of the barrel 20. Furthermore, the nib holder 22 has a cylindrical portion 28 of reduced diameter arranged within the barrel 20.

A rod 30 having a channel or passage 32 is tightly inserted into the center bore of the nib holder 22. The nib holder 22, furthermore, has a recess 34 of substantially semi-circular shape at its right-hand-end, said recess being capable of receiving and holding a nib 36 in a customary manner.

An ink supply sac 38 of elastic material, preferably of rubber, is tightly attached with its open end to the portion 28 of reduced diameter of the nib holder 22. The ink supply sac 38 is arranged within the barrel 20. The channel or passage 32 connects the interior of the ink supply sac 38 with the nib 36, so that ink contained by the ink supply sac 38 may be supplied to the nib 36.

An actuating member or actuating knob generally indicated by 40 having a cylindrical portion of reduced diameter is rotatably inserted on the left-hand-end of the barrel 20 as viewed in Figs. 1 and 2. A shoulder formed between said portion 42 of reduced diameter and the main body of the actuating knob 40 acts as an abutment engaged with the left-hand-end surface of the barrel 20. One end of a helical spring 44 is inserted into a bore 46 of the portion 42 of the actuating knob 40, and the other end of said helical spring 44 is inserted into a bore 48 of the portion 24 of the nib holder 22. Thus, the helical spring 44 surrounding the ink supply sac 38 is positively connected with the actuating knob 40 of the nib holder 22.

As best shown in Figs. 1 and 2, a portion of the helical spring 44 embraces a portion 50 of still further reduced diameter of the actuating knob 40 and another portion of the helical spring 44 embraces the end of the ink supply sac 38 where it is attached to the portion 28 of the nib holder 22.

Moreover, the portion 50 of the actuating knob 40 has a recess 52 arranged for receiving the closed end of the ink supply sac 38.

As shown in Fig. 1, the barrel 20 is removably inserted into the bore of a covering shell 54. A cap 56 may be loosely engaged with said shell 54 for protecting the nib 36 when the fountain pen is not in use.

If it is desired to fill the ink supply sac 38 with ink, the fountain pin is manipulated in the following manner:

The cap 56 is removed from the shell 54 and the shell 54 is removed from the barrel 20.

Now the actuating knob 40 may be turned with the fingers of a hand in the direction of the arrow shown in Fig. 2. Such a rotation of the actuating knob 40 causes a contraction of the coils and a movement of the coils relative to each other. These features in turn cause, firstly, a tightening of the ink supply sac on the portion 28 of the nib holder 22 by the portion of the helical spring 44 embracing the end of the ink supply sac, so that the ink supply sac 38 is prevented from rotation relative to the nib holder 22, if after a period of use the elasticity inherent to the ink supply sac 38 should not be any longer sufficient to hold the ink supply sac tightly on the portion 28 of the nib holder 22, and cause, secondly, a twisting of the ink supply sac 38 as shown in Figs. 2 and 5. This twisting of the ink supply sac 38 may be performed so effectively, that all the air previously inside of the ink supply sac 38 is expelled.

Now after a release of the actuating knob 40 the helical spring 44 returns same automatically into its original position and permits the elastic ink supply sac 38 to assume its original expanded condition, whereby ink is sucked into the ink supply sac 38 through the passage 32 immersed at the nib end into the ink of an ink bottle.

If desired, the twisting of the ink supply sac 38 by rotating the actuating knob 40 for filling purposes may be repeated several times.

In the embodiment of a fountain pen shown in Figs. 6-10, the nib holder 122 is again inserted into the right-hand-end of a barrel 120. The portion 128 of the nib holder 122, however, has an angular recess 158 capable of receiving a thickened portion 160 of the elastic ink supply sac 138. Moreover, the barrel 120 is provided with an angular shoulder 162 capable of engagement with the end of the ink supply sac 138 attached to the portion 128 of the nib holder 122. Thus, the elastic ink supply sac 138 is tightly held on the portion 128 of the nib holder 122.

Furthermore, the ink supply sac 138 has at its left-hand closed end a solid extension 164 integral with its main body. Said solid extension 164 is provided with a bore 166 registering with a bore of the actuating knob 140 rotatably engaged with the left-hand opening of the barrel 120. A pin 168 inserted into said registering bores of the actuating knob 140 and the solid extension 164 of the ink supply sac 138 causes a rigid connection between the actuating knob 140 and the ink supply sac 138. It will be readily understood that a rotation of the actuating knob 140 causes a twisting of the ink supply sac 138 as shown in Figs. 7 and 9.

Of course, the fountain pen shown in Fig. 6 may also be enclosed in a shell and a cap as shown in connection with the embodiment of the fountain pen illustrated by Fig. 1.

If it is desired to fill the fountain pen shown in Figs. 6 and 7, the actuating knob 140 is rotated back and forth whereby ink is sucked into the elastic ink supply sac 138 by the twisting and releasing thereof. Of course, the elasticity inherent to the ink supply sac 138 contributes to a

return movement of the actuating knob 140 from the position shown in Fig. 7 into the position shown in Fig. 6.

I have described preferred embodiments of my invention, but it is understood that this disclosure is for the purpose of illustration and that various omissions or changes in shape, proportion, and arrangement of parts, as well as the substitution of equivalent elements for those, herein shown and described, may be made without departing from the spirit and scope of the invention as set forth in the appended claims.

What I claim is:

1. A fountain pen comprising: a barrel being open at both ends, a nib holder inserted into a first opening of said barrel with one of its ends projecting from said barrel and with its other end being positioned within said barrel, a nib attached to the projecting end of said nib holder, an ink supply sac of elastic material tightly attached to the other end of said nib holder and arranged within said barrel, a passage in said nib holder connecting the interior of said ink supply sac with said nib, an actuating knob rotatably engaged with the second opening of said barrel, and a helical spring surrounding said ink supply sac, one end of said helical spring being connected to said actuating knob, and the other end of said helical spring being connected to said nib holder.

2. In a fountain pen as claimed in claim 1, said nib holder having a portion of reduced cross-section at its end positioned within the barrel, said ink supply sac being attached to said portion, and a part of said helical coil embracing the end of said ink supply sac attached to said portion of the nib holder.

3. A fountain pen comprising: a barrel being open at both ends, a nib holder inserted into a first opening of said barrel with one of its ends projecting from said barrel and with its other end being positioned within said barrel, a nib attached to the projecting end of said nib holder, an ink supply sac of elastic material tightly attached to the other end of said nib holder and arranged within said barrel, a passage in said nib holder connecting the interior of said ink supply sac with said nib, an actuating knob rotatably engaged with the second opening of said barrel, said actuating knob having a recess receiving the closed end of said ink supply sac, and a helical spring surrounding said ink supply sac, one end of said helical spring being connected to said actuating knob, and the other end of said helical spring being connected to said nib holder.
